UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK.

PROTECTING MEANS FOR TRANSMISSION SYSTEMS.

1,225,587.

Specification of Letters Patent.

Patented May 8, 1917.

Application filed May 14, 1913. Serial No. 767,543.

To all whom it may concern:

Be it known that I, ELMER E. F. CREIGHTON, a citizen of the United States, residing at Schenectady, in the county of Schenectady, 5 State of New York, have invented certain new and useful Improvements in Protecting Means for Transmission Systems, of which the following is a specification.

My invention relates to transmission systems and the object of my invention is to provide for the protection of transmission systems against the production and continuance thereon of certain unduly high voltages and the prevention of oscillations of 15 the energy thereon, produced by the discharge of energy from or to one or more of the conductors of the transmission system.

Various causes produce discharges of energy between conductors of a transmission system, and between a conductor of a system and ground. Such discharges often take place through the air between a grounded metallic body and a conductor, or between conductors. Such an arc is oscillatory in character unless special provisions are made and as a result gives rise to oscillations of energy on the system which are likely to produce disastrous results to the attached apparatus, as by the building up of 20 potential in a manner well understood. I accomplish the object of my invention, as set forth above, by requiring that a necessary exchange of energy between conductors of a system or between a conductor and ground take place at a certain point by reducing the insulation value at this point or otherwise localizing the discharge, and requiring that the discharge energy pass 25 through a resistance of approximately the critical value. In one aspect of my invention, it is immaterial whether the discharge takes place from one conductor of current to another conductor of current, completing a circuit through the arc, or whether the discharge takes place between a conductor of a 30 system of distribution, as one plate of a condenser, and another conducting body, as the earth, as another plate of a condenser. In either case the discharge may be said to take place between two conductors. As is well known, a discharge of electrical energy through a resistance of, or greater than, the critical value is aperiodic, hence such a discharge cannot produce oscillations of the

energy on the system. The critical value of 55 the resistance, as is well understood, depends upon the inductance and capacity of the system as a whole, or the part of the system immediately related to the discharge point.

It is not necessary that the resistance be of exactly the critical value. If it is greater than the critical value, the only effect is, that the discharge of energy over it takes an unnecessarily long time, and even though 65 the resistance is of very much less than the critical value, the advantages of my invention are obtained. For example, though the resistance used is of a value of but one-tenth the critical value, the oscillatory character is 70 very materially changed for although the discharge is still oscillatory the number of oscillations is strictly limited. Therefore, if the particular system to which my invention may be applied is capable of standing 75 the occurrence of a number of oscillations without the development of a fault, it is quite possible to use a resistance having a value very considerably less than the critical value, even less than one-tenth of the 80 critical value. For this reason the word "approximately" as hereinafter used in the specification and claims must be given a very broad interpretation for I intend the expression "approximately equal to the critical value", and similar expressions, to include resistances of the critical value, resistances between the critical value and even less than one-tenth of the critical value, and resistances of a somewhat greater value than 85 the critical value.

In carrying out my invention with overhead transmission lines employing metal towers or masts it is convenient to mount an arcing ring on the insulator carrying the 95 conductor and connect this ring to the mast or tower through a resistance member so that the total resistance offered to a discharge from or to that conductor is of approximately the critical value. It is only 100 necessary as will be understood, to connect the resistance to whatever metallic body is most likely to receive the discharge and insulate the metallic body except for this connection. In systems using an overhead 105 ground wire, a path of approximately critical resistance would be maintained between sections of the ground wire and ground in the

5 manner illustrated, in principle, in Figure 2. In the case of underground systems the conductors are generally carried through cables having metallic sheaths. Any discharge from conductor to ground, therefore, takes place through the metallic sheath. I prefer with such systems, therefore, to carry out my invention by keeping the sheath out of general connection with the earth by insulating it in any manner and connecting the sheath to the earth at one or more points through a resistance or resistances of approximately the critical value. A discharge to ground from one of the conductors, therefore, takes place to the sheath and through its connection, to ground.

10 The novel features of my invention may be embodied in a number of different constructions. In the accompanying drawings which form a part of this specification, I have illustrated diagrammatically two possible constructions embodying the novel features of my invention in which: Fig. 1 illustrates one way of applying my invention to an overhead transmission line, and Fig. 2 illustrates the principle of my invention as applied to a cable.

15 In Fig. 1 the mast 1 carries suitable arms 2 for supporting the insulators carrying the conductors. The insulator 3 is carried on a pin 4 attached to one of the arms of the mast. On this insulator is carried the conductor 5. In carrying out my invention with such an overhead transmission line it is satisfactory to attach the resistance member to the mast at one end and the other end to any metallic body which is so located as to most likely receive the arc from the adjacent conductor, this metallic body being insulated other than through the resistance. 20 In this particular case I have illustrated an arcing ring 6 of common construction, carried on the insulator 3. Electrically connected to the arcing ring 6 is the resistance 45 7 which is also connected, as shown, to the adjacent arm 2 of the mast 1. As before pointed out, the resistance member must be of such value that a resistance of approximately the critical value is offered to a discharge from the conductor 5 through the arcing ring 6 and the resistance 7. The arcing ring 6 is of course, so located that it is a part of the path of lowest resistance for any discharge which may take place from the conductor 5 or at least for any discharge which may take place from a given part of the conductor 5, the system as a whole being thus protected against discharges where their occurrence would be especially dangerous or undesirable.

25 In Fig. 2 is shown a cable 10 having the customary metallic sheath, usually of lead. This cable is shown, merely for purposes of illustration, as carrying three conductors. 30 Connected to the sheath of the cable is a con-

70 nector or connectors 11, the resistance of each of which is of approximately the critical value, the other end of each connector 11 being grounded at 12. The cable is insulated from the ground other than through the connectors. Now it is possible to attach a number of the grounding connections to a cable, preferably spacing them approximately equal distances apart, the sheath of the cable being continuous electrically. It 75 may also be desirable at times to break the sheath into sections insulated from each other, as shown at 13. In this case each section should have one or more grounded connections.

80 By this construction surges or oscillatory discharges occurring on any conductor of the cable are removed from the conductor and prevented from building up voltage peaks, due to the fact that the cable sheath 85 forms with its path to ground an inductively related circuit of approximately critical resistance, whereby upon the occurrence of an oscillatory surge, energy is induced from the conductor to the inductively related circuit 90 and such energy removed from the conductor to ground as an aperiodic discharge. Applying these principles of protection to an overhead ground wire system, the ground wire would be connected to earth in sections, 95 through resistance paths of approximately critical value and therefore in like manner would remove from the conductor any oscillatory disturbances as aperiodic discharges.

100 What I claim as new and desire to secure by Letters Patent of the United States, is:

1. The combination with an electrical conductor, of means located in proximity to said conductor for localizing discharges from said conductor, supports for said means providing paths to ground from said means, and means connecting said supports and said first mentioned means co-operating with said supports to provide paths having a resistance sufficient to render discharges 110 over said paths non-oscillatory.

2. The combination with an electrical conductor, of an insulated metallic member positioned relative to said conductor to receive any discharges therefrom, a path to ground 115 from said member including a support for said member, and a resistance between said member and said support of a value which provides said path with a total resistance sufficient to render all discharges over the 120 same non-oscillatory.

3. The combination with an electrical conductor, of an insulated metallic member positioned relative to said conductor to reduce the insulation value of said conductor 125 at that point, a support for said member, and a resistance between said member and said support which combined with the resistance of said support provides a path having a total resistance to conduct all dis- 130

charges to ground and render them non-
oscillatory.

4. The combination with an electrical conductor, an insulating support therefor, an
5 arcing ring carried by said support, and a connection to ground from said ring having
a resistance of approximately critical value.

In witness whereof, I have hereunto set
my hand this 12th day of May 1913.

ELMER E. F. CREIGHTON.
